US00D992815S

(12) **United States Design Patent** (10) Patent No.: **US D992,815 S**
(45) Date of Patent: **** Jul. 18, 2023**

(54) **PHOTONIC SKIN DEPILATOR**

(71) Applicant: **Shenzhen Greatro Electronic Technology Co., Ltd.**, Guangdong (CN)

(72) Inventors: **Leming Yang**, Guangdong (CN); **Jianhua Zheng**, Guangdong (CN); **Guohui Li**, Guangdong (CN)

(73) Assignee: **Shenzhen Greatro Electronic Technology Co., Ltd.**, Shenzhen (CN)

(**) Term: **15 Years**

(21) Appl. No.: **29/797,754**

(22) Filed: **Jul. 2, 2021**

(51) LOC (14) Cl. **28-03**

(52) U.S. Cl.

USPC **D28/44.1**; D24/209; D24/214

Primary Examiner — Jennifer Rivard

(57) **CLAIM**

The ornamental design for a photonic skin depilator, as shown and described.

DESCRIPTION

FIG. 1 is a front elevational view of a photonic skin depilator showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and right side perspective view thereof;

FIG. 8 is a top, rear and left side perspective view thereof;

FIG. 9 is a bottom, front and left side perspective view thereof; and,

FIG. 10 is a bottom, front and right side perspective view thereof.
